GAS DISCHARGE TUBE

Heinrich Kniepkamp, Berlin-Pankow, Germany,
assignor to Siemens and Halske Aktiengesellschaft,
Siemensstadt-Berlin, Germany, a corporation of Germany

Application December 18, 1937, Serial No. 180,475
In Germany December 29, 1936

5 Claims. (Cl. 250—27.5)

This invention relates to electron discharge devices, particularly to high voltage grid controlled gas discharge devices.

As long as the voltages which are handled in an electric discharge vessel do not surpass a certain limit, it is not difficult to obtain reliable operation. But as soon as higher potentials are used, it becomes increasingly difficult to insure reliable operation of the device because of the ever-present risk and danger of back-arching and flashing. Another unfavorable factor resides in the wall charges, for these are liable to lead to unexpected and undesirable discharges, for instance, in the form of sliding or creeping discharges or sparks. Discharges of this latter kind are likely to release occluded gases from the glass wall or shell which are very annoying and troublesome, and under certain circumstances they may render operation of the discharge vessel impossible. Efforts to eliminate these discharges have heretofore been attempted by so forming the electrode system that the configuration or pattern of the electrical field would not favor such discharges. Another remedy, in arrangements known in the prior art has been that the entire discharge path, including electrodes, was surrounded by a screen or shield optionally serving also for control purposes, or by forming the electrodes in such a manner that they would embrace or surround one another. However, even in such an arrangement interstitial spaces or openings exist through which the electrons moving at a high velocity are enabled to reach the walls of the vessels from the discharge space proper where they may build up undesirable charges. Moreover, the heat produced on the electrodes, owing to the thermal shielding by the screen (control grid) or as a result of the nesting into one another of the electrodes may be carried off only with great difficulty. This again promotes undesirable discharges and more particularly back-arching.

The object of this invention is to provide an improved electron discharge device of the grid controlled gas discharge type particularly suitable for use at high voltages, and particularly such a device in which back-arching or flash-over is substantially eliminated.

According to the invention, the plate and the control electrodes have planar surfaces facing each other and they have a sectional form such that the discharge space intervening between the electrodes connects with the ambient space only through a narrow tortuous gap. The rest of the two electrodes are exposed to the interior of the tube envelope and do not enclose each other with

the result that both of the electrodes are able to unimpededly radiate the heat dissipated in them.

The novel features which I believe to be characteristic of this invention are set forth with particularity in the appended claims, but the invention itself will best be understood by reference to the following description taken in connection with the accompanying drawing in which Figure 1 is a vertical section of an electron discharge device made according to this invention and Figure 2 is a vertical section of details of a modification of this invention.

The essential features of the invention will be understood most clearly by reference to the accompanying drawing. In Figure 1, confined within the tube envelope 1 which contains a gaseous medium, are a cathode 2, a plate or anode 3, and a control grid 4 forming the electrode assembly. The cathode 2 by the aid of the supporting rods 5 which at the same time function as current supply leads is anchored in the press 6. In the embodiment here shown the filament or cathode is of the hollow type, although it will be understood that any other type of cathode or source of electron supply may be used in connection with the invention. The discharge space 7 is surrounded by a shield or screen 8 which at one end supports the control grid 4. The said control grid just like the plate is preferably made of graphite. This insures two advantages in that both secondary emission may be practically suppressed by convenient choice of the material and that satisfactory conditions for conducting away and radiating the heat are secured. For the same purpose, the thickness of the graphite grid is chosen comparatively great, the desideratum being to make the area 9 radiating off heat from the grid as large as possible. For instance, it has been found to be quite advantageous to choose the thickness of the grid not less than one-tenth the grid diameter. The drawing clearly shows what viewpoints are essential in choosing the sectional form of the electrodes facing each other. The continuous annular projection 10 of the control grid must so engage in the annular groove 11 of the plate or anode that between the two surfaces 12 and 13 there remains but a narrow gap of, say, 1-2 mm. width. Such electrons as happen to have an outwardly directed speed component would then have to pass through this gap between the interfitting projections and recesses surrounding the discharge space between the electrodes, and they would have to alter the sense of their flight several times. As a consequence

they would be so impeded in their motion that practically no electrons at all would be able to escape from the discharge space and reach the wall or shell of glass. The space 14, as will thus be seen, is entirely shut off from the discharge. But in the case of this invention, and contradistinct to what is true of arrangements known in the prior art, this merit is not intended with the short-coming of poor thermal abdication. The distance between the surface 15 of the anode and the surface 16 of the grid is chosen of an approximate order of magnitude of the free length of path of the electrons, with a view to precluding back-lighting. The control grid 4 is provided with a number of slender channels 17 for the passage of the discharge.

The discharge vessel comprising an electrode assembly built in a way as hereinbefore disclosed will evidence no undesirable discharges even when operating with potentials between 20 and 30 kv.

The cross-sectional forms of the electrodes facing each other according to the invention may be chosen in different ways. But care must be taken so that the discharge space between the electrodes is separated from the ambient by a gap presenting several changes in directions or curves. For instance, the groove or curves could also be formed in the control grid, while the anode or plate is provided with an extension or elevation designed to fit into a groove of the control grid. This is shown, for instance, in Figure 2. In this exemplified embodiment the anode or plate 18 has a collar 19 which engages in a matching groove 20 of the control grid 21.

While in the exemplified embodiments here disclosed, graphite has been mentioned as a particularly advantageous material to use for the two electrodes facing each other, it is entirely possible, inside the scope and spirit of the invention, to build these electrodes of a different kind of material, more particularly materials possessing high heat conducting qualities. Where electrodes made of sheet-metal are used it will frequently prove advantageous to provide these with heat radiating ribs or fins to still further improve the conditions of getting rid of dissipated heat.

While I have indicated the preferred embodiments of this invention of which I am now aware and have also indicated only one specific application for which this invention may be employed, it will be apparent that this invention is by no means limited to the exact forms illustrated or the use indicated, but that many variations may be made in the particular structure used and the purpose for which it is employed without departing from the scope of this invention as set forth in the appended claims.

What I claim as new is:

1. An electron discharge device having an envelope containing a gaseous atmosphere, a cathode within said envelope for emitting electrons and an anode electrode for receiving said electrons, a tubular control electrode completely enclosing said cathode for segregating said cathode and anode and having a perforated surface through which an electron discharge can take place, said anode electrode having a surface presented across an intervening electrode free space to the perforated surface of the control electrode for receiving the discharge, one of said surfaces being provided with a continuous groove and the other of said surfaces with a continuous projection fitted within said groove but out of contact with the walls of said groove to provide a tortuous gap sur-

rounding the discharge path between said surfaces of the anode and control electrode.

2. An electron discharge device having an envelope containing a gaseous atmosphere, a cathode within said envelope for emitting electrons and an anode for receiving said electrons, a tubular control electrode completely enclosing said cathode for segregating said cathode and anode and having a perforated surface through which an electron discharge can take place, said anode having a surface presented across an intervening electrode free space to the perforated surface of the control electrode for receiving the discharge, said anode surface being provided with a continuous groove, and said control electrode having a continuous projection surrounding the perforated surface and extending within said groove out of contact with the walls of said groove to provide a tortuous gap around the discharge path between said surfaces of said anode and control electrode.

3. An electron discharge device having an envelope containing a gaseous atmosphere, a cathode for emitting electrons within said envelope, and an anode for receiving said electrons, a tubular control electrode completely enclosing said cathode for segregating said cathode and anode and having a perforated surface through which an electron discharge can take place, said anode having a surface presented across an intervening electrode free space to the perforated surface of the control electrode for receiving the discharge, said surfaces being provided with interfitting projections and recesses surrounding the discharge space, said interfitting projections and recesses being spaced to provide a tortuous gap surrounding the discharge path between the anode and control electrode.

4. An electron discharge device having an envelope containing a gaseous atmosphere, a cathode within said envelope for emitting electrons and an anode for receiving said electrons, a tubular control electrode surrounding said cathode and closed at one end by a disc-like carbon member provided with perforations through which electrons can pass, said anode having a surface opposite said disc-like carbon member for receiving electrons passing through the perforations in said disc-like carbon member, an annular groove surrounding said surface of said anode and an annular projection on said disc-like carbon member surrounding the perforated surface of said disc-like carbon member and extending into said groove but out of contact with the walls of said groove for providing a tortuous gap surrounding the discharge path between the facing surfaces of the anode and control electrode.

5. An electron discharge device having a gaseous atmosphere and containing a cathode for emitting electrons and an anode for receiving said electrons, a tubular control electrode surrounding said cathode and having a closure member at each end, one of said closure members being provided with perforations through which electrons can pass to the anode, said anode having a surface presented to the surface of said perforated closure member, one of said surfaces being provided with a continuous groove and the other of said surfaces with a continuous projection extending into said groove but out of contact with the walls of the groove for providing a tortuous gap surrounding the discharge space between the opposed surfaces of the anode and closure member.
